UNITED STATES PATENT OFFICE.

ALFRED W. CHAPMAN, OF CLEVELAND, OHIO, ASSIGNOR TO THE DONLEY BROTHERS COMPANY, OF CLEVELAND, OHIO, A CORPORATION.

WINDOW-FRAME FILLER AND GUIDE.

Application filed August 21, 1926. Serial No. 130,678.

This invention relates to window frames of steel, or other metal, set in masonry building construction, and appertains more particularly to means for effecting tight joints between such metal frames and brick-work.

In the setting of steel window frames in masonry, and especially in walls of brick, as such frames are usually fashioned, it has been found difficult, and an unstable practice, to fill and point with mortar the vertically disposed chinks left open between the bricks and the outer side rails of the frames. And a further inconvenience arises from the absence in steel window frames of any sort of guide for the bricks to abut against in laying up the outer face of the wall adjoining the frame. These structural deficiencies lead to error, bad workmanship and vexatious impediments in the setting of such frames, and are likely to result in imperfect outer joints at the sides of the frames, which soon crumble on exposure to bad weather and the jarring of traffic.

Thus the prime object of the present invention is to provide efficient and practical means for overcoming the aforesaid incongruities, and which will facilitate the setting of metal window frames in masonry walls in a workmanlike and durable manner. Another important object is to produce an inexpensive attachment that can be quickly and easily applied to the frames, adjusted for position, and readily detached for fitting to peculiarities of the setting. A further purpose is to furnish a filler and guide strip that may be sprung on to the side rails of a sash frame, but held rigidly in position when the frame is set in a wall.

Although the device is intended for use in any metal window or door frame to which it may be adapted, it is found especially advantageous in the construction of windows in basement walls of brick, such as shown in the accompanying drawing which I proceed to describe.

Fig. 1 of the drawing is an outside elevation of a steel and glazed window set in a masonry basement wall.

Fig. 2 is an enlarged and foreshortened vertical section taken on line 2-2 of Fig. 1.

Fig. 3 is a detailed horizontal section taken on line 3-3 of Fig. 2.

Fig. 4 is an end view of the filler and guide strip, and

Fig. 5 is a side view of the same.

The reference numeral 1 indicates a brick wall having a window aperture therein, the sides of which are shown at 2. To provide a lintel it is customary to span the window opening with a pair of angle irons 3 and 3' for supporting the overlaid brickwork 2', and these angles receive and hold between them the upper projecting vertical wing of the top T-rail 4 of the window frame; 60 which frame is a rectangle of T-bar with the stem of the T section projecting inwardly, its side rails being shown at 4' in Figs. 1 and 3, and its bottom rail at 4" in Figs. 1 and 2. The spaces all around the frame 4 are filled with cement mortar, as shown, and it rests on the sill bricks 2" with a filling of mortar underneath.

The sash 5 is usually formed of T-bar also, a smaller size than the frame being 75 used, and it may be hinged to the frame rail 4 as at 6, Fig. 2. The sash is provided with glass panes 7 held in place by suitable clips and putty.

Now in this standard steel window and 80 masonry construction it will be noticed that, in order to lay the bricks flush at the outer face of the wall 1, elongated vertical chinks, somewhat wider than the thickness of the upright wing of the angle iron 3, are left 85 on each side of the window opening between the side rails 4' of the frame and the brick sides 2. These chinks extend the full height of the window aperture, are bothersome to fill and point with mortar, and such filling 90 under ordinary conditions soon crumbles and falls out. To remedy this defect I provide a filler strip 8 of sheet metal bent in a U-shape lengthwise, which forms a deep groove therein fitted to be sprung over the 95 outer wing of the side rail 4' of the frame, and held thereon by friction. The outside margin of the strip 8 is bent to form a flange 9 projecting at right angles to its body part, as best shown in Figs. 4 and 5.

Thus the flange 9 of the filler strip forms a guide for the bricks to abut against in laying up the wall 2, for the flange should be wide enough to overlap the wall somewhat. The said flange also covers the chink 100 between the frame rail 4' and the bricks 2, so that cement mortar 10, Fig. 3, can be compacted in said chink against the strip 8 and its flange to form a durable and invisible joint.

100

105

110

The strip 8 should be of copper-steel, or a metal that resists oxidation and corrosion, so that its exposed flange will stand the weather. And it should now be readily seen that before setting in the wall the strips 8 can be shifted in position along the frame rail, or removed from the frame and fitted to sloping sills or other conditions, but that after setting these strips are permanently fixed.

I further point out and distinctly claim as my invention:—

1. An attachment for a metal window frame comprising a sheet metal strip having a deep longitudinal groove formed therein to receive and to frictionally engage a side rail of said frame, and a flange projecting

outwardly at right angles to the body portion of said strip.

2. In a metal window frame, a side rail of said frame provided with a detachable sheet metal strip sprung thereon so as to frictionally embrace said rail, and a flanged margin of said strip projecting outwardly at right angles to the frame.

3. In a metal window frame, a side rail of said frame, a sheet metal strip having a deep longitudinal groove formed therein adapting it to be sprung on and to frictionally embrace said side rail, and a flanged margin of said strip extended outwardly at right angles to said side rail.

ALFRED W. CHAPMAN.
